CLAIM

The ornamental design for a vehicle display screen or portion thereof with a graphical user interface, as shown and described.

DESCRIPTION

FIG. 1 is a front view of a vehicle display screen or portion thereof with a graphical user interface showing our new design according to a first embodiment thereof;
FIG. 2 is a front view of a vehicle display screen or portion thereof with a graphical user interface showing our new design according to a second embodiment thereof;
FIG. 3 is a front view of a vehicle display screen or portion thereof with a graphical user interface showing our new design according to a third embodiment thereof;
FIG. 4 is a front view of a vehicle display screen or portion thereof with a graphical user interface showing our new design according to a fourth embodiment thereof; and,
FIG. 5 is a front view of a vehicle display screen or portion thereof with a graphical user interface showing our new design according to a fifth embodiment thereof.

(Continued)

The broken lines in FIGS. 1-5, showing the vehicle display screen or portions of the graphical user interface, are used to illustrate portions of the article; all broken lines form no part of the claimed design.
